Primary Examiner—Philip S. Hyder**[57] CLAIM**

The ornamental design for a pill holder and dispenser, as shown and described.

DESCRIPTION

FIG. 1 is a top plan view of a pill holder and dispenser showing my new design;

FIG. 2 is a front elevational view thereof;

FIG. 3 is a right side elevational view thereof, the left side elevational view being a mirror image thereof;

FIG. 4 is a bottom plan view thereof;

FIG. 5 is a rear elevational view thereof; and,

FIG. 6 is a top front perspective exploded view of the lid and base thereof.
